SINK REFUSE SCOOP

Herman L. Adelstein, Upland, Calif.

Application May 11, 1934, Serial No. 725,141

10 Claims. (Cl. 15—105)

This invention relates to a scoop more particularly intended as a kitchen utensil to be used for handling garbage, but also capable of being used for other purposes.

5 An object of the invention is to provide a scoop of the kind stated which will be of a sanitary character and which combines with its sanitary features improved means for draining surplus liquid from the refuse or garbage being removed by its use.

Another object of the invention is to provide a scoop for household use which is furnished with means to lift by suction small, flat objects that could not be readily picked up by an ordinary 15 scoop, dust pan or shovel.

Still another object is to provide an improved sanitary cover member for the purpose of completely housing in the garbage being conveyed by the scoop.

20 Yet other objects, advantages and features of invention may hereinafter appear.

Referring to the accompanying drawing, which illustrates what is at present deemed to be a preferred embodiment of the invention,

25 Fig. 1 is a perspective view of the device illustrating the manual manipulation thereof.

Fig. 2 is a longitudinal section thereof on line 2—2 of Fig. 1.

Fig. 3 is a fragmental front elevation illustrating the relation of the cover member when closed to the front part of the scoop body.

Referring in detail to the drawing, the container or body portion 5 of the scoop is desirably composed of sheet metal and is shown having 35 a generally rectangular floor 6 furnished at the back with an upstanding wall 7 and at each side with an upright wall 8, said walls 8 being each downwardly inclined at 9 at the front end of the scoop. These three walls are preferably 40 formed as flanges, being parts of the same sheet of metal as the floor or bottom member 6. The rear corners of the scoop may be chamfered as indicated at 1c.

The scoop body 5 is furnished with a twisted 45 wire handle shank 10, said wire being desirably made of two strands 10a, and the upper edges of the wall members 7, 1c, and 8 are shown curled over thus forming, along the upstanding sides of the scoop, a continuous tubular member 12 which grips each strand 10a of the wire member 10. The outer end portion of the member 10 is embedded in the handle proper 13.

50 A resilient cover plate 15, provided with a mounting and operating member 16, is arranged to be swung to and from a closing position with

relation to the scoop body. Said member 16 has secured to it intermediate its ends a clip 17 which is pivoted at 18 to a bracket 19 secured to the front end portion of the handle proper 13.

The member 16, like the handle shank 10, is shown made of a two-strand twisted wire, said wire having a looped end portion 21, covered by a sheet metal clip 21a, to form a thumb hold at one side of the pivot 18, and having attached thereto, at the other side of said pivot, one end 10 of a tension spring 22, the opposite end of said spring being attached to the handle shank 10. 5

Therefore by pressing the thumb upon the clip 21a the operator may lift the cover plate 15 to the open position against the opposition of the 15 spring 22.

The cover plate 15 is made sufficiently narrow to fit between the side walls 8 when said cover is in the closed position. To the outer edge portion of said plate 15 is secured an elastic lip 20 member 25, preferably a sheet or thin plate of rubber, having corrugations or scallops 26 along its outer edge. Said lip 25 is shown attached to the cover plate 15 by means of a clamping plate 27 and rivets 28, the flat end body portion of said 25 member 25 being gripped between the plates 15 and 27, and its corrugated portion 26 projecting beyond the outer edge of the cover plate and also above and below the plane thereof.

The scoop floor or bottom 6 is also shown provided with a lip member 30 consisting of a somewhat flexible rubber plate, which is clamped to the edge portion of the bottom plate 6 by means of an overlying clamping plate 31 and rivets 32. Said cover lip 26 comes into a superimposed 30 relation to the lip 30 when the cover is closed, this arrangement adapting the device for more readily draining the liquid from the garbage in the scoop, each of the corrugations 26 providing a vent passage 26a under the closed cover for 35 this purpose.

When the cover plate 15 is permitted to assume the closed position under the urge of the spring 22, it presses down upon any garbage contained 40 within the scoop and thus squeezes the garbage 45 sufficiently to cause the water or other liquid to exude therefrom and, (assuming that the scoop is held in a downwardly tilted position) to flow out thru the vent passages 26a under the corrugations 26.

50 The tensility of the spring 22 also causes the corrugations 26 to press against the opposite lip 30 with sufficient force to assume a collapsed position thus modifying the size of the openings between said corrugations and said lip 30 55

to prevent foul, solid or semi-solid matter from exuding therethru when it is desired to drain the garbage contents of the scoop by holding the device with the mouth thereof directed down-
wardly.

5 The corrugated rubber portion of the cover, (being of a resiliently flexible character) also adapts it for being used to pick up adhesively small objects such as tea leaves and the like from
10 a sink bottom or plane damp surface on account of the reflex action of the corrugations as they assume their normal position after being depressed, the scoop being held in an inverted position when this is done. The grooves between
15 the corrugations deepen as the pressure is relaxed thus causing a gripping action upon objects within them as the corrugations reassume their original form.

I claim:

20 1. In a scoop of the class described, a container having a handle member attached thereto, and a cover for said container pivotally mounted upon said handle member, said cover having a resilient or elastic corrugated portion adapted for use in
25 picking up small objects on account of the reflex action of the elastic portion as the same assumes its original position after being abnormally constrained.

2. A scoop of the class described having a cover
30 plate furnished with a corrugated lip of elastic sheet material adapted for use in picking up small objects by depressing it and then permitting it to assume its original position.

3. A device of the class described comprising a
35 scoop provided with a somewhat resilient lip, and a cover pivotally connected therewith for movement to and from a closed position with said scoop, said cover having a corrugated lip portion adapted to be brought into intimate compressed
40 relation with said lip to provide drainage of liquid from the contents of the scoop while said cover is closed.

4. A device of the class described having a scoop, a cover plate hingedly connected therewith
45 and movable into a closing position with said scoop to compress the contents thereof, said cover

plate having a collapsible corrugated portion adapted to be brought into intimate contact with said scoop to provide passages for draining said device.

5. A device of the class described comprising a
5 scoop having upstanding side walls and a pivotally mounted cover plate having a working fit between said walls, said cover plate having a body portion which flexes longitudinally whereby to adapt it to conform itself more closely to the contents of the scoop, and having also a corrugated lip portion of elastic material to provide seepage passages between the cover and the scoop when said cover and said scoop are brought into intimate relation, and means urging said cover plate 15 and said scoop toward each other.

6. In a device of the character described, a scoop, a cover for said scoop, a lip carried by the scoop and a corrugated lip carried by said cover, and means tending to collapse the corrugations 20 of the cover against the lip of the scoop.

7. In a device of the class described, a scoop, and a flexible cover plate hingedly connected with said scoop, said cover plate having a collapsible corrugated lip.

25 8. In a kitchen utensil, a garbage collector comprising a scoop, a flexible cover plate hingedly connected with said scoop, and means automatically urging the free edge of said plate into intimate contact with said scoop while a part of said 30 plate nearer its hinge remains unsupported whereby said plate is caused to flex longitudinally.

9. In a kitchen utensil, a garbage collector comprising a scoop portion and a lid portion, a flexible lip carried by said scoop and a flexible 35 corrugated lip carried by said lid, and means urging the collapse of the corrugations against the lip of the scoop whereby to provide seepage passages for draining the contents of the scoop.

10. A garbage collecting utensil comprising a 40 scoop section and a lid section hinged to said scoop section, said lid section having a lip portion consisting of a resiliently flexible corrugated sheet material adapted to adhere to and remove thin light objects from a plane surface.

45 HERMAN L. ADELSTEIN.
